CLAIM

The ornamental design for a hard disc recorder as shown and described.

DESCRIPTION

FIG. 1. is a front perspective view of a hard disc recorder showing a first embodiment of our new design;

FIG. 2. is a front view thereof;

FIG. 3. is a rear view thereof;

FIG. 4. is a right side view thereof;

FIG. 5. is a left side view thereof;

FIG. 6. is a top plan view thereof;

FIG. 7. is a bottom plan view thereof;

FIG. 8. is an enlarged view of a part 8 shown in FIG. 2;

FIG. 9. is a front perspective view of a hard disc recorder showing a second embodiment of our new design;

FIG. 10. is a front view thereof;

FIG. 11. is a rear view thereof;

FIG. 12. is a right side view thereof;

FIG. 13. is a left side view thereof;

FIG. 14. is a top plan view thereof;

FIG. 15. is a bottom plan view thereof; and,

FIG. 16. is an enlarged view of a part 16 shown in FIG. 10. The broken lines shown represent portions of the hard disc recorder and form no part of the claimed design.

The dash-dot lines represent the boundaries of the enlarged parts and form no part of the claimed design.

1 Claim, 16 Drawing Sheets
